CARCASS TONGUE PROTECTOR

Andrew S. Hartanov, Chicago, Ill., assignor to
Industrial Patents Corporation, Chicago, Ill., a
corporation of Delaware

Application March 31, 1937, Serial No. 134,169

4 Claims.

(Cl. 17—1)

This invention relates to means for protecting the tongue of a carcass during processing.

One of the objects of the invention is to provide means for protecting a hog tongue from the teeth and from the dehairing beaters during dehairing of the carcass.

Other objects of the invention will be apparent from the description and claims which follow.

Figure 1 is a plan view of one embodiment of the present invention.

Figure 2 is a side view of the device shown in Figure 1.

Figure 3 is a perspective view of another embodiment of the present invention.

15 The tongue protector of the present invention may employ any desired type of means for holding the device in the carcass head. The holding means shown in the drawing is preferably prepared of spring wire provided with a closed loop 20 1 at one end for insertion in the hog's throat. Closed loop 1 comprises sides 2 and 3, apex 4, and shoulders 5 and 6 merging respectively into resilient side arms 7 and 8. Side arms 7 and 8 are affixed to resilient ball 9. Ball 9 is preferably 25 made of rubber.

In employing this embodiment of the present invention, the device is inserted in the animal's mouth, whereby the ball holds the mouth slightly open, so that should a portion of the tongue enter 30 the section of the mouth between the teeth it is not damaged.

The rubber ball is inserted into the animal's mouth on top of the tongue and set in between the teeth, resting against the roof of the mouth. 35 This keeps the jaws separated a predetermined distance, depending upon the size of the separator.

Hog tongue protectors have been proposed from time to time which involve maintaining the 40 jaws separate to prevent contact of the moving lower jaw with the tongue during dehairing.

Tongue protectors of such design have been unsuccessful in practice due to the tendency of the lower jaw to fracture when struck by the dehairing beaters.

The device of the present invention permits the 5 jaws to be separated and yet provides what is tantamount to the natural cushioning effect of unseparated jaws due to the resiliency of the separator.

In the modification of the device shown in Figure 10 3, the separator 10 is a resilient plate shaped to fit the mouth. The preferred material from which separator 10 is prepared is rubber tough enough so as not to be damaged by the teeth and yet possessing sufficient flexibility to take the 15 shocks to which it is subjected during the dehairing of the hog.

I claim:

1. A tongue protector comprising holding 20 means and a resilient ball.

2. A tongue protector adapted to contract when pressure is applied thereto thereby changing its normal shape and which will readily assume its normal shape upon release of pressure thereon and means for holding the protector in functional 25 relation with the tongue of a carcass.

3. In a tongue protector, a resilient ball adapted to contract when pressure is applied thereto thereby changing its normal shape and which will readily assume its normal shape upon release 30 of pressure thereon and means for holding the protector in functional relation with the tongue of a carcass.

4. In a tongue protector, a resilient plate adapted to contract when pressure is applied 35 thereto thereby changing its normal shape and which will readily assume its normal shape upon release of pressure thereon and means for holding the protector in functional relation with the tongue of a carcass.

40 ANDREW S. HARTANOV.
